TOY HOOP CONTROL WAND

Wilton L. Turner and John Randolph Ingram, both of
Oakmont Drive, Asheboro, N.C.

Filed May 26, 1965, Ser. No. 85,470

Term of patent 14 years

(Cl. D34—5)

FIG. 1 is a top plan view of the toy hoop control wand showing our new design;

FIG. 2 is a side elevational view of the wand of FIG. 1;

FIG. 3 is a bottom plan view of the wand of FIGS. 1 and 2;

FIG. 4 is an enlarged end elevational view of the wand as viewed from the left of FIG. 1;

FIG. 5 is a vertical sectional view taken on the line 5—5 of FIG. 4;

FIG. 6 is an enlarged vertical sectional view taken on the line 6—6 of FIG. 2; and

FIG. 7 is a perspective view of the wand.

We claim:

The ornamental design for a toy hoop control wand, as shown.
